(57) **CLAIM**

The ornamental design for a portable toilet seat for children, as shown and described.

DESCRIPTION

FIG. 1 is a perspective view of a portable toilet seat for children showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom side perspective view thereof;

FIG. 9 is in FIG. 1;

FIG. 10 is in FIG. 8; and,

FIG. 11 is in FIG. 7.

The broken lines in the drawings depict portions of the portable seat for children that form no part of the claimed design. The broken lines showing the enlargements in FIGS. 1 and 7-11 form no part of the claimed design.
